UNITED STATES PATENT OFFICE.

CHARLES E. REED, OF CHICAGO, ILLINOIS, ASSIGNOR TO CHARLES E. REED & CO., OF CHICAGO, ILLINOIS, A CORPORATION.

MACHINE FOR CUTTING PATTERNS.

SPECIFICATION forming part of Letters Patent No. 687,066, dated November 19, 1901.

Application filed April 1, 1901. Serial No. 53,846. (No model.)

To all whom it may concern:

Be it known that I, CHARLES E. REED, a citizen of the United States, residing at Chicago, county of Cook, State of Illinois, have invented a new and useful Improvement in Machines for Cutting Patterns, of which the following is a specification.

My invention relates particularly to that portion of the machine known as the "adjusting mechanism," by which the change of size is effected.

In my reissued Patent No. 11,569, dated September 29, 1896, I have described a machine to which my present invention is applicable, and it is designed to be an improvement upon the adjustment shown therein.

The object of my invention is to provide an adjustment which will be accurate without lost motion and quickly and easily operated.

It consists of details hereinafter more fully described, and particularly pointed out in the claims.

Figure 1 is a side elevation of a machine, showing my invention. Fig. 2 is a sectional view on lines 2 2, Fig. 4. Fig. 3 is a top plan view of a portion of a machine, showing my invention. Fig. 4 is a side elevation of the adjusting mechanism in detail. Fig. 5 is a plan view of a part of Fig. 4.

A represents the frame of the machine; B, the tracer; C, the cutter; D, the pattern; E, the pantographic frame; F, the rollers upon which the pantographic frame moves; G, the arm attached to the pantographic frame by which it is moved; H, the adjustment by which the movement of the arms is regulated; I, the guide the adjustment moves in; J, the driving mechanism; K, the gripping-lever of the adjustment; L, the collar against which it grips; M, the drum upon which the wire is wound; N, the wire; O, the set-nut; P, the binding-post; Q, the shoe which slides in the guide I; R, the arbor about the adjustment; S, the stop on the arbor by which the swing of the gripping-lever is limited; T, the pivot the guide swings upon, and U the bracket by which the pivot is supported.

The operation of my machine as a whole is the same as that described in the before-mentioned patent, the model pattern D at the tracer directing the travel of the cutter in

the usual manner, and the change of size being effected in the usual manner by the movement of the adjustment; but my new adjustment differs from the old in essential features. The shoe S, having tapering sides, slides in the guide I, which has inclined faces to correspond. While the cutting is being done and it is necessary to hold it securely to prevent its longitudinal movement the set-nut O is tightened, drawing up the shoe against the guide, through the post P, causing the shoe to bind in the guide. When the adjustment is to be moved to be set for another size, the set-nut is released and the gripping-lever K is applied to take hold of the collar L and turned to one side or the other, according to the direction it is desired to move the adjustment. The drum M is attached to the collar L and the wire N is wrapped one or two turns around it and has each end attached at or near the ends of the flange I', which extends along the guide I. The gripping-lever is loosely mounted on the post P; but by pressing down on the lever K it grips the collar L, and then by moving it in one direction or the other the drum is turned and the wire is wound around it and the adjustment moved up or down the guide, according to the movement of the lever. When the desired position is found, it is retained by turning up the set-nut O, as above described, until the pattern is cut. Then it is released and set for another size by means of the gripping-lever. The arm G, by which the pantographic frame is moved, is attached to the post P and moves with the adjustment. The amount of movement of the adjustment is measured by the swing of the gripper, and this is regulated by adjusting the stop S to allow it a longer or shorter stroke, one stroke being ordinarily sufficient to effect a single change of size in the pattern. The gripping-face of the gripper is roughened or milled and also the face of the collar which it grips upon in order to prevent slippage. The guide is curved on the arc of a circle and is pivoted in the bracket U.

What I claim, and desire to secure by Letters Patent, is—

1. In a pattern-cutting machine, the herein-described adjustment, consisting of the combination of the movable member Q, the

guide I in which said member Q moves, the drum M, attached to said movable member, the wire N, wrapped about said drum, the gripping-lever K, attached to said drum, and 5 the arm G, carried by said movable member, all substantially as shown and described.

2. In a pattern-cutting machine the herein-described adjustment, consisting of the combination of the movable member Q, the 10 guide I in which said member slides, the drum M, attached to said movable member, the wire N, wrapped about said drum, the collar L, attached to said drum, the gripping-lever K, which grips said collar, and the arm G, carried by said movable member, all substantially as shown and described.

3. In a pattern-cutting machine, the herein-described adjustment, consisting of the combination of the movable member Q, the 20 guide I, in which said movable member moves, the drum M, attached to said movable member, the wire N, wrapped about said drum, the gripping-lever K attached to said drum, the set-nut O, by which said movable member 25 is held stationary, and the arm G, carried by said movable member, all substantially as shown and described.

4. In a pattern-cutting machine, the here-

in-described adjustment, consisting of the combination of the shoe Q, the guide I, in 30 which said shoe slides, the binding-post P, upon which said shoe is mounted, the drum M, loosely mounted upon said binding-post, the wire N about said drum, the gripping-lever K, for turning said drum, the set-nut O, 35 for binding said shoe to said guide, and the arm G, carried by said shoe, all substantially as shown and described.

5. In a pattern-cutting machine, the herein-described adjustment, consisting of the 40 combination of the shoe Q, having sloping faces, the guide I, in which said shoe slides, having corresponding faces, the binding-post P, upon which said shoe is mounted, the drum M, loosely mounted upon said binding-post, the wire N, about said drum, the collar L, attached to said drum, the gripping-lever K, loosely mounted upon said binding-post, the set-nut O, for binding said shoe to said 45 guide, and the arm G, carried by said shoe, 50 all substantially as shown and described.

CHARLES E. REED.
